UNITED STATES PATENT OFFICE.

LOUIE A. SHERMAN, OF KANSAS CITY, MISSOURI, ASSIGNOR, BY DIRECT AND MESNE ASSIGNMENTS, OF ONE-FOURTH TO HARRY E. SHERMAN AND ONE-HALF TO O. K. HERNDON, BOTH OF KANSAS CITY, MISSOURI.

VULCANIZING-MATERIAL-CONTAINING PACKAGE.

1,356,662.

Specification of Letters Patent. Patented Oct. 26, 1920.

Application filed April 19, 1920. Serial No. 374,791.

To all whom it may concern:

Be it known that I, LOUIE A. SHERMAN, a citizen of the United States, residing at Kansas City, in the county of Jackson and State of Missouri, have invented certain new and useful Improvements in Vulcanizing-Material-Containing Packages; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to a heat generating package to contain materials for use in vulcanizing and one of the objects thereof is to provide a package which will conveniently contain the necessary materials for vulcanizing a patch upon a main body as, for example, a vehicle tire.

The manner of carrying out the vulcanizing operation is so well understood that it is deemed unnecessary to specifically describe the steps in this application. Suffice it to say that the package consists of two nesting, interchangeable members, one of which contains, as a part thereof, the patch and the other the heat generating material, the patch containing member being normally nested within the other member to protect the heat generating material when the device is not in use. The patch containing member, however, is removable and is adapted to receive the member containing the heat generating material in nested relation so that when the heat generating material is ignited and burns to generate the heat, the patch may be vulcanized to the main body of which it is to form a part. Therefore, when the package is not in use, both the patch and the heat generating material will be protected against loss as they will be contained between the two members, an advantage over forms of devices in which the heat generating material and the patch are exposed.

In the drawings,

Figure I is a perspective view of the package in its normal condition.

Fig. II is a bottom, perspective view of the package containing member or lid.

Fig. III is a bottom view showing the heat-

ing material-containing member nested in 55 the patch supporting member.

Fig. IV is a top, perspective view of the same, and

Fig. V is an enlarged, sectional view on 60 the line V—V of Fig. I.

The invention is shown as consisting of two members 1 and 2. The normal lower member 1 is provided with an upwardly projecting flange 3 having an enlarged offset member 4 to receive the member 2. The 65 outer diameter of the lower portion of the flange 3, however, is less than the inner diameter of the upwardly projecting flange 5 of the member 2 so that the two members may be interchangeably nested. That is, 70 the member 2 may fit into the offset, enlarged portion 4 of the flange 3 or the lower portion of the flange 3 may be received within the flange 5, as will be apparent hereafter.

The flange 3 is provided with outwardly projecting ears or lugs 6, which may be struck or bent out from the material of which the flange 3 consists and the flange 5 is provided with similar outstanding ears 80 or projections 7 so that these may be grasped in pulling the nested members 1 and 2 apart.

The member 2 normally constitutes the lid for the casing or primary member 1 and to the bottom or disk portions 8 of the member 85 2 is normally secured a vulcanizing patch 9 while the member 1 contains a body 10 of slow burning material to which is preferably applied an ignition cap 11, the ignition cap, however, forming no part of my 90 invention.

When the parts are in their normal position, that is, as shown in Figs. I and V, the member 2 serves as a cover or lid which protects the heat generating or combustible material 10 against deterioration or liability 95 of loss by becoming loose from its container and also insures the association of the patch with the package since the patch is inclosed by attaching it to the bottom of 100 the lid 2.

When, however, it is desired to carry out the vulcanizing operation, the lid 2, is removed from the member 1 and slipped over the bottom thereof, as shown in Figs. III 105 and IV, so that the patch 9 is at the bottom of the package and the heat generating body 10 is at the top. Then the ignition cap 11

may be ignited or, if the ignition cap is absent, a flame may be applied to the body 10 to start combustion, whereupon the slow burning material 10 will generate heat sufficient to carry out the vulcanizing process.

It will be seen from the foregoing that the liability of loss or deterioration of either of the essential elements of the package, that is, the patch or the heat generating materials, will be eliminated because these will normally be held by the two confining walls of the two members interchangeably nestable one within the other to either serve as an inclosing package or as a heat supplying medium to afford the necessary heat to permit the vulcanizing to take place.

What I claim and desire to secure by Letters-Patent is:

1. A vulcanizing material containing package consisting of two nesting members, one of which contains a heat generating material and the other a rubber patch.
2. A vulcanizing material containing pack-

age comprising two nesting members, a heat generating material in one member, the other member normally serving as a cover.

3. A vulcanizing material containing package comprising two interchangeable, nestable members, a heat generating material supported by one member and a rubber patch supported by the other member.

4. A vulcanizing material containing package comprising two nesting members, a rubber patch secured to the bottom of one member and a heat generating material contained within the other member.

5. A vulcanizing material containing package comprising two interchangeable, nestable members provided with manually engageable lugs or projections whereby they may be engaged to be separated, a patch carried by one member and a heat generating material supported by the other member.

In testimony whereof I affix my signature.

LOUIE A. SHERMAN.
